UNITED STATES PATENT OFFICE.

HERBERT E. BRIDGWATER, OF SYRACUSE, NEW YORK, ASSIGNOR TO REMINGTON TYPEWRITER COMPANY, OF ILION, NEW YORK, A CORPORATION OF NEW YORK.

TYPEWRITING MACHINE.

Application filed January 31, 1922. Serial No. 522,983.

To all whom it may concern:

Be it known that I, HERBERT E. BRIDGWATER, citizen of the United States, and resident of Syracuse, in the county of Onondaga and State of New York, have invented certain new and useful Improvements in Typewriting Machines, of which the following is a specification.

My present invention relates to typewriting machines and more particularly to what are known as collapsible or portable typewriters and to the type actions thereof. The main object of the invention is to provide new and improved type bar actuating mechanism and which is especially adapted for employment in a collapsible or portable typewriter wherein the type bars are collapsible.

To the above and other ends which will hereinafter appear, my invention consists in the features of construction, combinations of devices and arrangements of parts herein-after described and particularly pointed out in the claims.

In the accompanying drawings which illustrate the preferred form of my invention, Fig. 1 is a fragmentary top plan view of a portable or collapsible typewriting machine embodying my invention, only so much of the machine being shown as is necessary to a complete understanding of the invention.

Fig. 2 is a fragmentary vertical sectional view taken on a plane indicated by the section line 1—1 in Fig. 1 and looking in the direction of the arrows at said line, said Fig. 2 showing a type bar in compacted or lowered position however, whereas Fig. 1 shows the type bars raised for use.

Fig. 3 is a view corresponding to Fig. 2 but showing the type bar expanded or raised into position for use as in Fig. 1.

Fig. 4 is a fragmentary sectional view showing the type bar action of Fig. 3 in operated position, the lower case type being shown in printing contact with the platen.

Fig. 5 is a fragmentary transverse vertical sectional view taken on a plane indicated by the section line 2—2 in Fig. 1 and looking rearward in the direction of the arrows at said line.

The main frame of the machine comprises as clearly appears from Figs. 1 and 2, parallel vertical side plates or members 1 provided

at their front ends with inturned ears 2 to which are secured by screws 3 a cross member or comb plate 4 which guides the printing key-levers of the machine. The main frame further comprises a top plate 5 suitably secured to certain of the frame members. Suitably supported on the main frame is a traveling platen carriage (not shown) 6 on which is mounted a rotary platen 6 diagrammatically illustrated. The carriage may be and preferably is constructed and mounted as in the well-known Remington-portable typewriter, and combined with motor or spring drum devices and escapement mechanism of the character shown in the Remington-portable machine and disclosed in certain patents relating to said machine, as for example the patent to John H. Barr, No. 1,320,034, granted Oct. 28, 1919. Also I may and preferably do employ with my present invention means for shifting the carriage and platen transversely to change case, line spacing means, and ribbon feeding and other mechanisms, all of the character found in said Remington-portable machine.

In carrying out my invention in the present instance I provide a type bar support which is shiftably mounted for the purpose of enabling the type bar system to be alternately expanded for use, and compacted when in disuse to reduce the dimensions of the machine for convenient handling or boxing. Said type bar support is in the form preferably of a horizontally disposed segmental body 7 provided with lateral wings 8 cast integrally with the body and terminating in upright depending extensions or slide bars 9 formed along their outer faces with vertical V-grooves 10 (Figs. 1, 2 and 5). Oppositely facing co-operating V-grooves or seats 11 are formed in the stationary track-bars 12. The opposing grooves or seats receive sets of rollers or balls 13 which are preferably associated with ordinary separators or controllers, roller bearings thus being provided for the support or segment 7, 8, 9. The track-bars 12 are preferably in the form of steel inserts which are fixedly set in rectangular grooves or depressions, indicated at 14, formed in upright track-bar holders 15. These track-bar holders form an integral part of a casting or frame piece

which preferably is made of aluminum and comprises a transverse body portion or bar 16 having near its ends forwardly extending webs 17 which connect the holders or bars 15 and their fixed tracks 12 to the body 16. The outer faces of the upright bars 15 are formed with bosses 18 threaded to receive headed screws 19 which rigidly secure the casting or member 15, 16 and the side frames 1 together, thus constituting said member a part of the main frame on which the segment 7, 8 is movably mounted by means of the ball bearings. These afford free up-and-down movement of said segment while at the same time maintaining the segment at all times in proper relationship to the main frame. The upper inclined face of the bar 16 has secured to it at its middle, by headed screws 20, a center guide member 21 which is inclined upward and rearward and terminates in a guide opening, indicated at 22, with which the type ends of the type bars are adapted to co-operate as they near the printing point on the top of the platen. Said type bars, each designated by the reference numeral 23, are arranged in an arc of a circle forward of the platen, being received in vertical slots indicated at 24 formed radially in the front and under portion of the segment 7, these guide slots radiating from a common center on the type guide 21 at the lower end of the guide opening 22. For the sake of convenience, only a few of the guide slots or kerfs 24 are illustrated in the drawings (Figs. 1, 2 and 5), but it is to be understood that the segment 7 is cut or formed with a full series of such slots sufficient to receive and guide a complete set of type bars 23. These type bars are mounted on a common arcuate pivot wire 25 which is received and housed in a slot formed horizontally in the upper portion of the segment 7 and indicated by the numeral 26. The free end of each type bar is provided with a type block 27 having two types, one lower case and one upper case. At the under side of the type bar opposite the type block is a rounded projection or nose 28 which, when the machine is compacted (as in Fig. 2) may contact with the top plate 5 or preferably with a pad 29 of compressed felt or the like which is secured in a slight countersink or depression in the top plate, said pad being arcuate and extending from one side of the top plate to the other near its front edge which may be rounded to provide a suitable finish. At this time when the machine is compacted and the type bars are in disuse their body portions are recumbent or substantially horizontally disposed, and, at a slight distance forward of their pivotal support 25, rest on and are supported at their under sides by fixed means, which, in the present instance, is in the form of an arcuate wire member or pillow 30 which is suitably fixed in a depression or seat 31 formed in the rear edge portion of the top plate 5. The support, member or rest 30 is fixed or stationary as contrasted with the shiftable rest of the Remington-portable machine. The upper side of the rest or pillow 30 projects somewhat above the upper surface of the top plate, and the rear upper side of said rest is also exposed so that the type bars when shifted may slide freely over and upon said rest. The heel portions or those portions of the type bars at the opposite sides of their fulcrums from the body portions, curve or extend downward when the type bars are in disuse, said heel portions passing through the slots 24. The heel of each type bar is provided with a cam or curved actuating slot indicated at 32. Co-operatively engaging with said slot is a headed actuating pin 33 which projects laterally from the rear end of an operating member or sub-lever 34, said lever underlying the associate type bar and having a yielding or floating support which is one of the important features of the present invention and will hereinafter be described in detail. The sub-levers 34 are levers of the first order and at their forward ends are pivotally connected at 35 with the upper ends of depending links 36, the lower ends of said links being pivotally connected at 37 with printing key levers 38. The pivotal connections 37 are in the form of pins projecting from the sides of the key levers, the links 36 being perforated to fit over said pins and being prevented from becoming accidentally detached by spring clips 39 secured to the sides of the key levers 38. Said key levers extend horizontally fore-and-aft of the machine and at their rear ends are formed with open-mouthed slots 40 to fit over and co-operate with a fulcrum wire 41 which is secured to the frame bar 16. The forward side of said bar is formed with a series of parallel guide slots or kerfs indicated at 42 in which the rear or pivoted portions of the key levers 38 are received and guided. Near their front ends said key levers pass through and are guided by the comb plate 4, said key levers terminating in upright portions or stems 38a which receive finger keys or buttons 43. The stems of the key levers are varied in height so as to provide rows or banks of different heights as is usual, there being four banks of keys in the present case. Preferably, the keyboard is enclosed in a U-shaped frame piece, not shown herein, but which may have rearwardly extending sides which are suitably attached to the main frame of the machine.

The type bars 23 are adapted to slide over the rest 30 in order to be elevated into a position for use, this being accomplished by shifting the segment or type bar support downward. With the type bars having a

pin-and-slot or direct connection with their sub-levers 34 it was found to be necessary in order to enable the type bar support to be freely shifted to expand the machine for use, 5 to provide a yielding fulcrum or support for the sub-levers. In the present instance this support is afforded by individual fulcrum arms 44, one for each sub-lever 34. The fulcrum arms are substantially upright when 10 the machine is in collapsed condition, each fulcrum arm being provided at its upper end with an open-mouthed slot indicated at 45 which receives a headed fulcrum pin 46 projecting laterally from the side of the 15 associate operating lever 34 between its ends and resting in the bottom of the slot, there being thus provided a fulcrum for the lever 34. The fulcrum arms 44 are pivotally supported at their lower ends on an arcuate 20 pivot wire 47 common to all of the fulcrum arms, and mounted in turn on a support 48 which is horizontally disposed forward of the type bar segment and is segmental in shape, being of considerably greater radius 25 than the type bar segment, so that the two supports or segments may in a sense be interseated. The segmental support 48 may be an aluminum casting provided with integral lateral extensions 49 which are angularly disposed, as clearly appears from Fig. 1, the outer faces of said extensions being flattened to fit between the side plates 1 with which they are held in fixed and rigid relationship as by headed screws 50. The lower 30 ends of the fulcrum arms 44 are received in and guided by slots or kerfs indicated at 51 formed in the rear portion of the segment 48, these guide slots 51 being radially formed and having the same center as the slots 24 35 in the segment 7, the two sets of slots being in line with each other as clearly appears from Fig. 1. It is to be understood that while for convenience of illustration the full showing of the slots 51 has been omitted 40 from the drawings, yet there is a complete series of said slots extending from one end to the other of the segment 48 which supports the sub-levers 34 and their fulcrum arms 44, said slots 51 corresponding in number to the slots 24 in the type bar segment 7. It will be seen that the type bars together with part of their type actions comprising the levers 34 radiate from a common center, while the key levers extend fore-and-aft of 45 the machine in substantial parallelism although slightly fanned outward at the sides of the system in order properly to space the keys in the keyboard. Also it will be apparent that the links 36 may be bent or 50 twisted in order properly to connect the sub-levers 34 with their key levers 38. Each type action is provided with spring restoring means which may comprise a coiled spring 52 hooked at its upper end through 55 a hole in the associate sub-lever 34 back of the fulcrum thereof, said spring extending downward and being anchored at its lower end to a spring plate 53. Said plate is suitably secured to the under face of the segment 48 and is arcuate in shape, the inner edge at 54 being inclined upward and rearward and being formed with a series of holes through which the lower ends of the springs 52 are hooked. The upper face of the segment 48 has suitably secured to it a horizontal plate 55 which is also arcuate in shape and is inclined upward at its inner edge as shown at 56, the face of this inclined portion 56 providing a rest or support for the sub-levers 34 when the machine is in use, said sub-levers having movements which may be said to be more or less fore-and-aft or horizontal during the expansion and compaction of the machine as distinguished from the vertical shifting movements of the type bar segment or support 7. The forward edge portion of the plate 55 is adapted to serve as a locking device, preventing operation of the type actions when depressed as in Fig. 2, a shoulder or hook 36^a with which each link 36 is provided contacting at this time with the plate 55 so as to prevent downward movement of the link under actuation of the associate key lever. 60

Hand operated means are provided for shifting the type bar support vertically in its bearings in order to compact the type bars and to raise or elevate them for use, said means comprising a rock shaft 57 arranged transversely of the machine in its base, and bearing at the ends in suitable openings in the side plates 1. A pair of crank arms 58 are mounted on the rock shaft 57, one being arranged near each end of the shaft inside the neighboring side plate 1. Each crank arm 58 is provided with a collar 59 which receives a cross pin 60 whereby the crank arm is fixed to the shaft. The outer end of each crank arm is pivotally connected as by a headed and shouldered rivet 61 with one end of a link 62, the opposite end of said link bearing on the shouldered portion of a screw 63 which is threaded into a lug 9^a projecting forward from the associate extensions 9 on the type bar segment 7, 8. Said segment is thus connected at each end with the rock shaft 57 by trains of devices which are in effect toggles, each toggle comprising two elements, viz., a link 62 and arm 58 which are pivotally connected together at 61, to provide a toggle-joint which may be opened or straightened and also partially closed by rotary movements communicated to the rock shaft 57. Such movements may be conveniently communicated to the shaft by a crank arm 64, having a collar 65 fixed to the right-hand end of the shaft, the crank arm being outside the right-hand side plate 1 and the collar bearing therein. A headed screw 65^a threaded into the left-hand end 100

105

110

115

120

125

130

of the shaft 57 cooperates with the outer face of the left-hand end plate 1 to prevent endwise movement of the shaft towards the right. The outer end of the crank arm 64 terminates in a laterally projecting head 66 which houses a poppet stud and also supports a convenient finger piece (Figs. 1 and 5). The housing 66 is bored out as indicated at 67 to receive the poppet stud or pin 68 which is provided with a flange 69 and carries outside the housing 66 a cap 70 which fits over the end of the housing and affords means for pulling the poppet stud longitudinally outward against the force of its spring and also for adjusting the crank arm 64. Said spring 71 is coiled around the stem of the stud and is confined between the bottom of the housing 66 and the flange 69. The inner end of the stud is adapted to cooperate with two holes 72 formed in the right-hand side plate 1, one hole located to lock the crank arm 64, the toggles 58, 62 and the type bar segment 7, 8 all in the position illustrated in Fig. 2 where the toggles are straightened, the segment is raised and the type bars lowered or compacted, the other hole 72 co-operating to lock the parts in the positions illustrated in Figs. 1, 3 and 5 where the toggles are broken, the type bar segment is lowered and the type bars raised in position for use. Excessive downward movement of the segment 7, 8 is prevented by angular stop pieces 73 which are secured at their outer ends by screws 74 to the bottom of the track bars 15, the lower end portions of said stop pieces projecting into the path of the slide bars 9, the bottoms of said slide bars being adapted to contact with and rest on said stop pieces or plates 73 as shown in Figs. 3 and 5. In Fig. 2 the typewriting machine is shown in collapsed or compacted position at which time it will be observed the bodies of the type bars are recumbent or supine, being substantially horizontally disposed and in contact at their forward ends with the pad or plate 5. Just forward of said pivots the bottom edges of the bars rest on the rest 30 which is substantially in the horizontal plane of the top or printing face of the platen, the pivots of the type bars being at this time close to said plane. The toggle elements 58 and 62 are substantially straight so that the weight of the type bar segment is largely sustained by the toggles and the rock shaft 57. Also at this time the fulcrum arms 44 are substantially upright. When it is desired to expand the machine for use the poppet or locking pin 68 is first withdrawn from the rear hole 72, leaving the crank arm 64 free to be swung forward until the poppet 68 is brought opposite the forward hole 72 and locked therein. This forward movement of the crank arm rocks the shaft 57 and breaks the toggles 58, 62, swinging the toggle elements into the angular relationship shown in Fig. 3 and causing the segment to be shifted or lowered vertically downward on the trackways 12 to its lower position where it is supported by the stop plates 73. This shifting movement in the present instance is about three-quarters of an inch in length. As a result the shifted segment 7 is brought down to a position where it stands slightly higher than the stationary segment 48 and behind said segment 48. The lowering of the segment 7 correspondingly lowers the fulcrum wire 25 and causes a bodily movement of all of the type bars simultaneously in correspondence with the bodily movement of the segment 7 on which they are supported. As the type bars are shifted bodily simultaneously downward they will slide over the stationary rest 30 and as the fulcrum wire 25 moves downward below said rest the bars will swing pivotally on said wire, changing their angular relationship with the segment and being raised or elevated at their type ends to the position shown in Fig. 3. From this figure it will be observed that while the combined bodily and pivotal movement of the type bars has not brought them to an exactly vertical position yet they are substantially upright and are supported by the rest 30 above their pivots in position to be actuated to print when their key levers are depressed. The raising or elevation of the type bars from compacted to expanded position by moving or sliding over their stationary rest is permitted by reason of the fact that the fulcrums of the levers 34 are floating or yieldingly mounted so that the levers may all simultaneously move or yield to the shifting of the type bars, these movements carrying the said levers from the Fig. 2 position radially outward to the Fig. 3 position. The levers 34 near the middle of the machine will have a substantially forward movement. While the motions of the outer levers of the series will include lateral or sidewise components, still to a considerable extent their movement is also forward. The fulcrums 46 of the sub-levers or levers 34 also move forward, and at the same time are slightly lowered due to the fact that the fulcrum arms 44 swing downward from the upright position to the inclined position illustrated in Fig. 3. This forward movement of the sub-levers swings the upper end portions of the links 36 forward about their pivotal connections 37, which latter remain stationary, and this swinging movement of the links clears the locking shoulders 36^a from the locking plate 55, thus unlocking the type actions so that they may be readily operated by depression of the printing keys 43. When one of the printing key levers is depressed the parts of the type action will

70 75 80 85 90 95 100 105 110 115 120 125 130

- be swung from the Fig. 3 position to the position illustrated in Fig. 4, the link 36 pulling down the forward arm of the sub-lever 34 and raising the rear arm thereof, 5 causing the actuating pin 33 on said arm to traverse the cam slot 32 and swing the type bar downward with an accelerating motion due to the relationship of the pin-and-slot connection between the type bar and its sub-lever. This accelerating action continues as the type bar approaches the platen and the actuating pin 33 approaches the fulcrum 25 of the type bar until the type bar is within an inch or so of the platen and the pin approaches the end of the slot 32, after which the pin begins to recede from the type bar pivot. The accelerating action of the present type bar system is similar in results to that of the 10 No. 10 Remington typewriting machine. With the parts related as in Figs. 3 and 4, the platen at this time being in its forward or lower case position, the inner or lower case type on the actuated type bar will cooperate with the platen to make an imprint. 15 It will be understood that when it is desired to print in upper case the platen is shifted rearward to the dotted line position of Fig. 4 and that this case shifting movement 20 of the platen is entirely distinct from and bears no direct relationship to the shifting movement of the type bar segment for compacting and expanding the machine. It will further be noted that during the printing actuation of the type bar the bodily location of the fulcrum of the sub-lever 34 will not be disturbed, the fulcrum arm remaining in contact with the rest or stop 56. 25 On releasing the actuated printing key the parts will be restored to normal position by the action of the restoring spring 52.
- The machine is compacted or compressed and the type bars simultaneously restored from the position of use (Fig. 3) to the position of disuse (Fig. 2) by manipulating the crank arm 64, swinging it back to its rearmost position, straightening the toggles, raising the type bar segment and causing the type bars to slide or move over their stationary or fixed rest from the Fig. 3 to the Fig. 2 position. 30
- While, when compacted or collapsed the machine is substantially of the height of the present Remington-portable typewriter it will be understood that as a result of the simplification of the type actions and the elimination of parts, it is possible so to design the machine as that it may be reduced in height to a considerable extent. 35
- Various changes may be made without departing from my invention. 40
- What I claim as new and desire to secure by Letters Patent, is:—
1. In a typewriting machine, the combination with a set of key actuated pivoted type 45 bars, of means operative to communicate simultaneously to all of said type bars compound bodily and pivotal movements, the bars being moved bodily with their pivots and at the same time turning on their pivots 50 so as to change the type bars from a condition of disuse to a condition wherein they may be actuated to print by their keys, such compound movement of the type bars changing the typewriting machine from a compact 55 or collapsed condition to an expanded or extended condition. 60
2. In a typewriting machine, the combination of a set of pivoted type bars, printing keys, levers operative by said keys and connected to said type bars, and means for bodily moving all of said type bars with their pivots simultaneously towards and away from their operating levers to predetermined positions, said type bars in one of said positions being operative to print when their keys are actuated and in the other of said predetermined positions being inoperative by their keys. 65
3. In a typewriting machine, the combination of a set of pivoted type bars, printing keys, levers operative by said keys and connected to said type bars, and means for bodily moving all of said type bars with their pivots simultaneously towards and away from their operating levers to predetermined positions and thus to effect expansion and compaction of said typewriting machine, the operating levers remaining stationary during such simultaneous bodily 70 movement of the type bars. 75
4. In a typewriting machine, the combination of a set of type bars each provided with a plurality of types, a shiftable support on which said type bars are pivoted, a platen 80 shiftable to change case, and means operative to elevate and depress said type bars so as to expand and compact the machine when said support is shifted, such shifting movement of the support taking place while the 85 platen and the body of the machine remain stationary. 90
5. In a typewriting machine, the combination of a set of pivoted type bars having an elevated position of use and a lower position 95 of disuse, a fixed rest with which the body portions of the type bars engage in both of said positions, and means for moving the set of type bars at a single operation from one of said positions to the other over said 100 rest. 105
6. In a compactible typewriting machine and in combination, a typewriter frame, a set of pivoted type-bars adapted to occupy a lower substantially horizontal inoperative 110 position and also an upright operative position, a shiftable support within said frame upon which said type bars are mounted, means for shifting said support, and means for turning said set of type bars collectively 115 120
- 65 125
- 65 130

during the shifting of said support; whereby said type bars may be moved from their inoperative to their operative position, and vice versa.

- 5 7. In a typewriting machine, the combination of a set of type bars capable of arrangement in two positions, in one of which the type bars are adapted for use in the typewriting machine as in expanded condition, 70
10 and in the other of which the type bars are in a position of disuse and the typewriting machine is in collapsed condition, a rest with which said type bars cooperate in both their positions, and means for 15
15 moving said type bars from one of said positions to the other independently of movement of said rest which remains stationary.

- 20 8. In a typewriting machine, the combination of a platen, a set of type bars each provided with a plurality of types, a support on which said type bars are pivoted, case shifting means, means independent of said case shifting means for simultaneously moving 25
25 all of said type bars from a position of disuse to a position in which they may be operated, and a type bar rest supporting said type bars in both of said positions, said rest being independent of said last recited means.

- 30 9. In a collapsible typewriting machine, the combination of horizontally disposed key levers, horizontally disposed type bars, a fixed rest on which said type bars are supported, connections between said type bars 90
35 and said key levers comprising horizontally disposed sub-levers, and means for expanding the machine for use by raising the type bars and changing their angular relationship with the key levers, the angular relationship of the sub-levers with the key levers being automatically changed at the same time.

- 40 10. In a collapsible typewriting machine, the combination of horizontally disposed key levers, horizontally supported type bars, connections between said type bars and said key levers comprising horizontally disposed sub-levers pivotally supported independently of the type bar support, and means for 45
50 expanding the machine for use by raising the type bars and changing their angular relationship with the key levers, while at the same time the angular relationship of the sub-levers with the key levers is automatically changed and the pivotal supports of said sub-levers are automatically shifted.

- 55 11. In combination with the base-frame of a collapsible typewriting machine, an arcuate type bar rest rigid with said frame, horizontally disposed key levers within said base frame, pivoted type bars arranged in an arc and horizontally disposed when in disuse and upright when in position for use, connections between said type bars and said 60
65 key levers, and means for changing simul-

taneously the angular relationship of all said type bars to said key levers and thus to expand and compact the machine, said rest supporting said type bars both when the machine is compacted and when it is expanded.

- 70 12. In a typewriting machine, the combination with the main frame of the machine, of a platen shiftable to change case, a type bar support slidably mounted thereon, type 75
75 bars pivoted on said support, each type bar being provided with a plurality of types, a rest for said type bars independent of said support, key levers independent of said support, connections between said type bars and said key levers, and key operated means for shifting said support to expand and compact the machine.

- 80 13. In a typewriting machine, the combination of a type bar support, bearings for said support, means for shifting said support vertically up and down, stop devices for limiting the downward movement of said support, type bars pivoted on said support, a rest for said type bars independent of 90
95 said support, key operated actuating means for said type bars independent of said support, and hand-controlled means for shifting said support and retaining it in shifted positions, the type bars being all simultaneously moved from a position of disuse into a position of use when said support is shifted downward and restored to a position of disuse when said support is shifted back to its upper position.

- 100 14. In a typewriting machine, the combination of horizontally disposed key levers, a vertically shiftable type bar support, a set of type bars pivoted on said support, connections between said type bars and said key levers, means supporting said type bars in a substantially horizontal position of disuse, said set of type bars being simultaneously raised into a position for use when said support is shifted downward.

- 110 15. In a typewriting machine, the combination of a vertically shiftable type bar segment, type bars pivoted on said segment, key connections for said type bars, a stationary rest for said type bars, and means for shifting said segment to simultaneously slide said type bars over said rest into and out of a position of disuse.

- 115 16. In a collapsible typewriting machine, the combination of a set of type bars, a rest therefor, and means for shifting said type bars simultaneously into and out of collapsed position by sliding said type bars over said rest while it remains motionless.

- 120 17. In a collapsible typewriting machine, the combination of a shiftable type bar segment, type bars pivoted on said segment, key connections for said type bars, a type bar rest independent of said segment and having a stationary support, and means 125
125

comprising sets of toggles for shifting said segment and sliding said type bars over said rest into and out of a position of disuse.

18. In a collapsible typewriting machine, the combination of a vertically shiftable type bar segment, stop devices for supporting said segment in its lower position, key operated type bars pivoted on said segment, a type bar rest mounted independently of said segment, and means comprising toggle devices for shifting said segment and moving said type bars over said rest out of and into collapsed position, the toggle elements when straightened supporting said segment 10 in its raised position.

19. In a collapsible typewriting machine, the combination of a vertically shiftable type bar segment, stop devices for supporting said segment in its lower position, key 20 operated type bars pivoted on said segment, a type bar rest mounted independently of said segment, means comprising toggle devices for shifting said segment and moving said type bars over said rest out of and into 25 compacted position, the toggle elements when straightened supporting said segment in its raised position, and hand-controlled locking devices for locking the segment in both of its shifted positions.

30 20. In a typewriting machine, the combination of a vertically shiftable type bar segment; roller bearings for said segment; type bars pivoted on said segment; key connections for said type bars; a stationary rest for 35 said type bars; and means for shifting said segment to simultaneously slide said type bars over said rest into and out of a position of disuse, said means comprising a key actuated rock shaft, and sets of toggles connected to said shaft and to said segment.

21. In a typewriting machine, the combination of a vertically shiftable type bar segment; roller bearings for said segment; type bars pivoted on said segment; key connections for said type bars; a stationary rest for 45 said type bars; and means for shifting said segment to simultaneously move said type bars over said rest into and out of a position of disuse, said means comprising a key actuated rock shaft, sets of toggles connected to said shaft and to said segment, an actuating arm fixed to said rock shaft and provided with a finger piece, and detent devices for retaining said arm in predetermined set positions.

50 22. In a typewriting machine, the combination of a horizontally arranged type bar segment, said segment being provided with lateral extensions or arms terminating in 60 vertical track-ways, stationary vertical track-ways opposite said first recited track-ways, roller bearings cooperating with said track-ways, type bars supported on said segment, trains of key actuated operating devices for said type bars, said trains com-

prising levers and fulcrum arms on which said levers are pivoted, a segmental support for said fulcrum arms provided with lateral extensions which are secured to the frame of the machine, said last recited support being 70 arranged forward of said first recited support, and means for shifting the type bar support up and down on said vertical bearings to simultaneously move all of the type bars into and out of a position of use, said 75 fulcrum arms and said levers receiving corresponding movements when the type bar support is shifted.

23. In a typewriting machine, the combination of a set of type bars, a type bar support formed with radial slots, a set of type bars seated in said slots, key levers fulcrumed independently of said support, connections between said key levers and said type bars comprising sub-levers, fulcrum arms for said sub-levers, a support provided with radial slots in which said fulcrum arms are seated, said support being mounted independently of the type bar support, the slots in the two supports radiating from a common 80 center, and hand-operated means for effecting relative shifting movements between said 85 two supports.

24. In a typewriting machine, the combination of type bars, a horizontal type bar 90 segment, key levers, connections between said key levers and said type bars comprising a set of sub-levers, a set of fulcrum arms on which said sub-levers are supported, and a segment for said fulcrum arms arranged 100 forward of said type bar segment.

25. In a typewriting machine, the combination of type bars, a horizontal type bar segment, key levers, connections between said key levers and said type bars comprising a 105 set of sub-levers, a set of fulcrum arms on which said sub-levers are supported, a segment for said fulcrum arms arranged forward of said type bar segment, a stationary rest for said type bars, and means for shifting 110 the segment while said rest remains motionless.

26. In a typewriting machine, the combination of type bars, a horizontal type bar segment, key levers, connections between 115 said key levers and said type bars comprising a set of sub-levers, a set of fulcrum arms on which said sub-levers are supported, a stationary segment for said fulcrum arms arranged forward of said type bar segment, a rest for said type bars, a rest for said fulcrum arms, and means for shifting said type bar segment to expand and compact the machine, the type bars sliding over their rest into and out of expanded position, and the fulcrum arms lying against their rest when the type bars are in expanded position.

27. In a typewriting machine, the combination of a set of type bars, a shiftable 120

type bar support on which said type bars are pivotally mounted, key levers fulcrumed independently of said support, connections between said key levers and said type bars 5 comprising sub-levers having fulcrums mounted independently of said type bar support, and hand-operated means for shifting said type bar support and said type bars, the fulcrums of said sub-levers being automatically shifted at the same time.

28. In a collapsible typewriting machine, the combination of a set of type bars, a support therefor, means for actuating the type bars comprising a set of sub-levers, and 15 means for expanding the machine for use by simultaneously moving all of the type bars and their support to a new position and at the same time automatically shifting said sub-levers.

29. In a typewriting machine, the combination of a set of type bars, key operated means for actuating said type bars comprising a set of sub-levers, swinging fulcrum arms on which said sub-levers are pivotally supported, and means for moving said type bars and automatically swinging said fulcrum arms to shift the pivots of said sub-levers.

30. In a typewriting machine, the combination of a set of type bars, sub-levers having pin-and-slot connections with said type bars, pivoted arms each providing a pivotal support for one of said sub-levers, key levers, links connecting said key levers with 35 said sub-levers, and means for moving said type bars and simultaneously swinging said arms to shift the pivots of the sub-levers.

31. In a typewriting machine, the combination of a set of type bars, a vertically 40 shiftable support on which said type bars are pivoted, a set of key levers, connections between said key levers and said type bars comprising a set of sub-levers, pivotal supports for said sub-levers, and means for shifting said type bar support vertically and at the same time shifting the pivotal supports for the sub-levers in a direction generally fore-and-aft of the machine as the type bar support is lowered and raised.

32. In a collapsible typewriting machine, the combination of a platen, a set of type bars adapted to strike on the top of said platen, said type bars being swung to print from a substantially upright position, 55 cam slots in said type bars, and key operated devices for actuating said type bars comprising pins engaging in said cam slots, certain of said key-operated devices yielding to permit the type bars to be swung forward and downward to a substantially horizontal position of disuse when the machine is compacted.

33. In type bar actuating mechanism for collapsible typewriting machines, a set of

key actuated levers provided with separate 65 and independent floating fulcrums and having actuating devices engaging cam slots in the type bars.

34. In a collapsible typewriting machine, the combination of a set of type bars, the body portions whereof are substantially horizontally disposed when in a condition of disuse, sub-levers having pin-and-slot connections with said type bars, upright fulcrum arms for said sub-levers having 70 a common pivotal support, springs for said sub-levers, horizontally disposed key levers, and upright links connecting said sub-levers with said key levers.

35. In type bar actuating mechanism for collapsible typewriting machines, the combination of a set of type bars, key actuated levers having accelerating connections with said type bars, floating fulcrums for said levers, said fulcrums being separate from each other, and means for moving the type bars from a collapsed position to a position for use, the floating fulcrums of said levers being correspondingly shifted.

36. In a collapsible typewriting machine, the combination of a set of type bars, a shiftable support on which they are pivoted, a set of sub-levers of the first order, pins on said sub-levers engaging cam slots in said type bars, depending links connected to the opposite arms of said sub-levers, and printing key levers to which the lower ends of said links are connected, the machine being expanded for use by shifting the pivotal support of the type bars.

37. In a collapsible typewriting machine, the combination of a top plate, a set of type bars having shiftable fulcrums, a set of sub-levers of the first order, pins on said sub-levers engaging cam slots in said type bars, depending links connected to the opposite arms of said sub-levers, and printing key levers to which the lower ends of said links are connected, the type bars when in disuse being substantially horizontally disposed and supported on the top plate of the machine, the machine being expanded for use by shifting the fulcrums of the type bars downward and raising their type ends from the top plate.

38. In a collapsible typewriting machine, the combination of a set of type bars, a set of key levers, connections between said type bars and said key levers comprising a set of links provided with locking devices, and a locking plate with which said locking devices co-operate when the type bars are in a position of disuse to lock the type bar actions.

39. In a collapsible typewriting machine, the combination of a set of type bars, a set of key levers, connections between said type bars and said key levers comprising a set of links provided with locking devices, and

a locking plate with which said locking devices co-operate when the type bars are in a position of disuse, said devices being swung out of engagement with said plate 5 when the type bars are moved into a position of use.

Signed at Syracuse, in the county of On-

ondaga and State of New York, this 28th day of January, A. D. 1922.

HERBERT E. BRIDGWATER.
